DESIGN FOR A SPINNING TOP

Louis Nagy and Elizabeth Zelenak,
East Dearborn, Mich.

Application September 15, 1934, Serial No. 53,300

Term of patent 3½ years

To whom it may concern:

Be it known, that we, Louis Nagy and Elizabeth Zelenak, citizens of the United States, residing at East Dearborn, in the county of Wayne and State of Michigan, have invented a new, original, and ornamental Design for a Spinning Top, of which the following is a specification, reference being had to the accompanying drawing, forming a part thereof, and in which—

We claim:—

The ornamental design for a spinning top, as shown.

LOUIS NAGY.
ELIZABETH ZELENAK.
